UNITED STATES PATENT OFFICE.

SCOTT NELSON, OF BROOKSTON, AND ELIJAH WOOD, OF REYNOLDS,
INDIANA.

LOCK.

SPECIFICATION forming part of Letters Patent No. 742,052, dated October 20, 1903.

Application filed March 26, 1903. Serial No. 149,684. (No model.)

To all whom it may concern:

Be it known that we, SCOTT NELSON, residing at Brookston, and ELIJAH WOOD, residing at Reynolds, in the county of White, State 5 of Indiana, citizens of the United States, have invented certain new and useful Improvements in Locks, of which the following is a specification.

This invention relates to locks, and has for 10 its object to provide an improved form of mortise-lock wherein the application of the lock to the edge of a door is greatly facilitated.

It is furthermore designed to provide an 15 improved spring-latch for manipulation by the usual door-knobs and having means to limit the rotation of the door-knobs, so as to obviate a double throw of the latch by a continuous rotation of the door-knob in one direction and also permit of slidable movements of the latch independently of the door-knob.

Another object of the invention is to provide an improved key-actuated bolt which is 20 locked against accidental movement at both its inner and outer limits.

With these and other objects in view the present invention consists in the combination and arrangement of parts, as will be herein- 25 after more fully described, shown in the accompanying drawings, and particularly pointed out in the appended claims.

In the drawings, Figure 1 is a vertical sectional view taken through a portion of a door 30 with the lock of the present invention fitted thereto and having parts broken away to show the movable elements thereof. Fig. 2 is a transverse sectional view on the line 2 2 of Fig. 1. Fig. 3 is an enlarged detail sectional 35 view taken through the tumbler of the spring-actuated latch. Fig. 4 is a similar view taken through the key-actuated bolt. Fig. 5 is a top plan view of the spring-actuated latch. Fig. 6 is a rear elevation of the latch. Fig. 40 Fig. 7 is an enlarged detail sectional view taken on the line 7 7 of Fig. 5. Fig. 8 is a bottom plan view of the key-actuated bolt. Fig. 9 is a detail perspective view of said bolt.

Like characters of reference designate cor- 45 responding parts in each and every figure of the drawings.

By reference more particularly to Figs. 1 and 8 of the drawings it will be seen that the present device embodies a face-plate 1, from which project a pair of upperspaced arms 2 and 55 an integral housing or casing 3, which are secured to the back of the face-plate in any suitable manner—as, for instance, by having their forward ends bent into outturned flanges riveted to the face-plate. Located between the 60 upper pair of arms 2 and substantially midway between the opposite ends of said arms is a plate 4, preferably in the form of a disk, having notches 5 in its opposite edges for the reception of the reduced portions of the 65 arms, as shown in Fig. 7. It will here be noted that the notches in the plate 4 are substantially T-shaped, and the flange portions of the notches are hammered or upset, so as to overlap the arms 2, and thereby connect 70 the plate rigidly thereto. A suitable opening 6 is formed centrally through the plate 4 for the slidable reception of the stem portion 7 of a latch-bolt, the beveled head 8 of which works through an opening in the face-plate. 75 Surrounding the bolt 7 is a helical spring 9, which bears in opposite directions against the plate 4 and the head of the bolt, so as to yieldably hold the latter at its outer limit. For manipulating the latch there is provided 80 a cylindrical tumbler 10, the opposite journal or hub portions 11 of which are rotatably mounted in corresponding circular openings 12 in the enlarged rear end portions of the arms 2. At the normally front side of the 85 tumbler is a perforate projection 13, with which is loosely engaged the hooked end 14 of a link 15. The forward end of the link 15 slides in a longitudinal slot 16 in the rear end 90 of the bolt 7, and said forward end is bent to 95 form an elongated loop or slotted portion 17 for the reception of a pin or key 18, which pierces the rear slotted end of the bolt. By this connection between the link and the bolt it will be seen that a rearward move- 100 ment of the link 15 will draw the bolt rearwardly, and by reason of the slot 16 the bolt may move rearwardly independently of the link 15 without turning the tumbler 10 and the door-knob spindle 19, which passes through the polygonal opening 20 in said tumbler. As best indicated in Fig. 6 of the

drawings, it will be seen that the rear end portions of the arms 2 are provided with lateral inwardly-directed projections 21, which extend across the periphery of the tumbler 5 at diametrically opposite points and in the path of the perforate ear or projection 13, thereby to form stops to limit the rotation of the tumbler, and thereby prevent continuous rotation of the door-knob spindle and in turn 10 prevent a double throwing of the latch.

The key-actuated bolt 22 is mounted in the integral housing or casing 3 and has a laterally-enlarged head 23 at its outer end working through a suitable opening in the face-plate. 15 The under edge of this bolt is provided with a front notch or seat 24 and a rear notch or seat 25, adapted to alternately receive the pin 26, carried transversely between the sides of the integral housing or casing 3 and designed to lock the bolt against accidental or unauthorized endwise movements. The top edge of the bolt 22 is cut away or recessed, as indicated at 27, and across this recess extends a longitudinal leaf-spring 28, the opposite ends of which are bifurcated, as at 29, so as to straddle the bolt, the latter being provided with front and rear shoulders 30 and 31 for engagement by the ends of the spring to prevent the latter from working in an endwise direction upon the bolt. Bearing upon an intermediate portion and across the top of the spring is a pin 32, which pierces the opposite sides of the integral housing or casing 3 and tends to place a tension upon the 35 spring, so as to normally hold the bolt in a depressed position. At the rear end of the bolt is an upper rearwardly-directed extension 33, the under side of which is provided with adjacent substantially semicircular notches or seats 34 and 35, of which the front notch 34 is in alignment with the keyhole-slot 36 of each side of the integral housing or casing 3, so as to receive the barrel of the key when the latter is inserted into the lock. 40 When a key is inserted into the lock with its barrel received in the seat 34 of the bolt and then turned so as to swing its bit upwardly into the seat 35 and then forwardly, the rear end of the bolt will be tilted upwardly against the action of the spring 28, so as to lift the bolt out of engagement with the pin 26 and then shoot the bolt forwardly until the bit of the key is turned downwardly, when the spring will force the bolt downwardly until 45 the rear notch or seat 25 engages the pin 26 and locks the bolt at its forward limit.

As best indicated in Fig. 8, it will be seen that the shank portion of the key-actuated bolt 22 is narrower than the space between the sides of the integral housing or casing 3, and to prevent lateral play of the bolt projections 40 are provided on opposite sides of the bolt near the rear end thereof, so as to work against the sides of the integral housing or casing 3, and thereby obviate lateral play of the bolt. To prevent the bit of a key from turning in the space between the bolt

and the integral housing or casing 3, the sides of which form guide-arms, projections 41 are provided upon the inner faces of the respective guide-arms of said integral housing or casing 3, so as to form stops to limit the rotation of the bit of a key, and thereby guide or direct the latter to the seat 34 of the bolt. 7c

In view of the fact that there are no side plates extending from top to bottom of the face-plate 1 the application of the lock is very quickly accomplished by boring upper and lower openings 37 and 38 in the front edge of the door 39 for the reception of the respective bolts, the face-plate 1 of course being let into the free edge of the door and the usual openings being provided in the door for the reception of the door-knob spindle and the key. 75 80 85

Having thus described the invention, what is claimed, and desired to be secured by Letters Patent, is—

1. In a lock, the combination with a face-plate, having guide members projected therefrom, of a bolt working between the members and through the face-plate, a tumbler mounted upon the members, a link pivoted at opposite ends to the tumbler and the bolt, and a stop projection carried by one of the members and lying in the path of the rear end of the link to limit the rotation of the tumbler. 90 95

2. In a lock, the combination with a face-plate, having guide members projected therefrom, of a bolt working between the members and through the face-plate, a tumbler rotatably mounted upon the guide members, a link pivotally connected at opposite ends to the tumbler and the bolt, and diametrically opposite stop projections carried by the guide members and directed across the periphery of the tumbler and in the path of the link to limit the rotation of the tumbler in opposite directions. 100 105

3. In a lock, the combination with a face-plate having guide members projected therefrom, of a guide-plate carried intermediately by the members and provided with a perforation, a bolt disposed between the guide members with its headed end working through the face-plate and its opposite longitudinally-slotted end working through the perforation in the guide-plate, a helical spring embracing the bolt and bearing in opposite directions against the head thereof and the guide-plate, a tumbler rotatably mounted upon the guide members in rear of the bolt, a link pivotally connected to the tumbler with its forward longitudinally-slotted end working in the slot of the bolt, a pin carried by the bolt 110 and piercing the slotted portions of said bolt and the link, and opposite stop projections carried by the guide members and projected across the periphery of the tumbler and in the path of the link to limit the rotation of the tumbler. 115 120 125

4. In a lock, the combination with a face-plate, having opposite guide members projected therefrom and provided with correspond-

ing keyhole-slots, of a bolt having its enlarged head working through the face-plate and its reduced portion working between the guide members, the under side of the shank being 5 provided with front and rear locking-notches and also provided with adjacent key-receiving seats at its rear end, the top portion of the shank being longitudinally recessed, a pin extending between the guide members 10 and disposed to be alternately received in the locking-notches of the bolt, a leaf-spring spanning the upper recessed portion of the bolt and having its opposite ends bifurcated to straddle the bolt at the opposite ends of the 15 recessed portion thereof, a pin extending between the guide members and bearing upon the top of the spring to yieldably hold the bolt in engagement with the locking-pin, and guide projections carried by opposite sides of 20 the bolt and working against the guide members, the bolt having a tilting movement under the action of a key to permit disengagement of the locking-notches from the locking-pin.

25 5. In a lock, the combination with a casing, of a slidable bolt having a longitudinal recess in one edge thereof, a leaf-spring carried by the bolt and straddling the recessed portion thereof and secured at its extremities to the 30 bolt, and a projection carried by the casing and frictionally bearing against the spring, whereby the bolt is capable of yielding laterally.

6. In a lock the combination with a casing, of a slidable bolt having a longitudinal recess 35 in one edge thereof, a leaf-spring spanning said recessed portion of the bolt, and having its opposite ends bifurcated to straddle the bolt at the opposite ends of the recessed portion thereof, and a projection carried by the 40 casing and frictionally bearing against the spring whereby the bolt is capable of yielding laterally.

7. In a lock, the combination with a face-plate, an integral housing or casing project- 45 ing therefrom, a slidable bolt moving in said housing or casing and depressed at its top portion, a spring fixed at each end to the upper edge of the bolt directly over the de- 50 pressed portion thereof, adjacent key-receiving seats formed in the under rear extremity of the bolt, the front receiving-seat being nor- mally in alignment with the keyhole, front locking-notches also formed in the under edge of said bolt, and a pin extending between 55 the side walls of said housing or casing to normally engage one of said front locking-notches.

In testimony whereof we affix our signatures in presence of two witnesses.
